Michael J. Kilroe

UNITED STATES PATENT OFFICE.

AXEL H. BURKEMAN, OF MINNEAPOLIS, MINNESOTA.

CAR DOOR.

Application filed August 27, 1925. Serial No. 52,780.

My present invention relates to car doors and has for its object to improve the same in the several particulars hereinafter noted.

To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary side elevation of a box car having the invention embodied therein;

15 Fig. 2 is a transverse vertical section, taken on the line 2—2 of Fig. 1;

Fig. 3 is a detail view in section, taken on the line 3—3 of Fig. 1, on an enlarged scale;

20 Fig. 4 is a fragmentary detail view with some parts sectioned on the line 4—4 of Fig. 1, on an enlarged scale;

Fig. 5 is a fragmentary horizontal section taken on the line 5—5 of Fig. 1, on an enlarged scale;

25 Fig. 6 is a fragmentary outside elevation of two of the door sections at their adjacent edges;

Fig. 7 is a fragmentary detail view in section, taken on the line 7—7 of Fig. 1, on an enlarged scale;

30 Figs. 8 and 9 are fragmentary perspective views of the parts shown in Fig. 7 separated; and

Fig. 10 is a fragmentary detail view principally in section, taken substantially on the line 10—10 of Fig. 1, on an enlarged scale.

The numeral 11 indicates the body of a box car and the numeral 12 indicates one of the side door openings therein.

40 The improved car door is mounted to close the door opening 12, and, as illustrated, comprises upper, lower and intermediate sections 13, 14 and 15, respectively, and as shown each thereof is made up of sheet metal but in some instances part wood may be used.

Said lower door section 15, at its lower horizontal edge, is slidably mounted on a track 16 secured to the car body 11 below the door opening 12 and extends to one side thereof. The upper door section 13 is slidably suspended from an overhead track 17 by means of a pair of brackets 18

having wheels 19 arranged to run on said track, and the intermediate door section 14 is slidably mounted on the two door sections 13 and 15.

An upright combined stop and cam-acting joint strip 20 is secured to the car body 11 at one side of its door opening 12 which limits the closing movements of the door sections and also forces the same against the car body 11 to form tight joints therebetween. Secured to the car body 11 at the rear ends of the tracks 16 and 17 is an upright bar 21 having an outturned stop 65 flange 22 which limits the opening movements of the door sections.

Each door section comprises inner and outer plates 23 and 24, respectively, the former of which has continuous inturned reinforcing flanges 25 at its marginal edges except at its rear end. To form a tight joint between the door sections, when closed, and the rear door post at the opening 12, there is pressed from each of said sections an upright bead 26 of the same depth as the flanges 25 and extends the full distance between the upper and lower members of said flanges 25. Outwardly pressed from each outer plate 24 are upper and lower horizontal reinforcing beads 27 and 28, respectively, and between said beads said plate is outwardly pressed substantially its entire length into concavo-convex form in vertical section.

To assist in supporting the rear ends of the door sections when open there is cut and pressed from the inner plate 23 of each of said sections an inwardly extended cam flange 29 arranged to ride, during the opening movement of said door, upon a cam flange 30 cut and pressed from the bar 21. By reference to Fig. 7, it will be noted that the cam flange 30 is upwardly inclined so as to draw the respective cam flange 29 inward 90 and hold the respective door section against outward movement from the car body 11.

For independently opening and closing the door sections, I provide toothed wheels 31 adapted to mesh with racks on said sections which consist of horizontally spaced seats 32 in the lower bead 28 of each door section. These seats 32 are formed by cutting the flat outer faces of the beads 28 on

oblique bisecting lines and then displacing the stock by pressing the same inward, as best shown in Figs. 3 and 6. The toothed wheels 31 are keyed to an upright shaft 33 journalized in upper and lower bearings 34 secured to the car body 11 with said shaft located outward of the door sections and directly in front of the door post at the rear of the door opening 12.

10 The shaft 33 extends below the car body 11 and has keyed thereto a ratchet wheel 35. A hollow operating lever 36 has a bifurcated head, the prongs of which are rotatably mounted on the lower ends of the shaft 33 with the ratchet wheel 35 located therebetween. A reversible pawl 37 is located between the prongs of the head of the operating lever 36 for engagement with the ratchet wheel 35, as best shown in Fig. 10. The 20 pawl 37 is secured to a stem 38 turnably mounted in the lever 36, and the outer end thereof is bent laterally to afford a crank by which said stem may be turned. A coiled spring 39, encircling the stem 38, is compressed between the pawl 37 and the inner end of the head of the operating lever 36. The pawl 37 is so designed that in moving the operating lever 36 in one direction, a step of movement will be imparted to the 25 ratchet wheel 35 and a reverse movement of said operating lever will cause said pawl to slide over the teeth of the ratchet wheel 35. The operating lever 36 is so located as to swing under the sills of the car body 11 and 30 is provided with a depending hand piece 40. This operating lever 36 is further provided with a U-shaped member 41 adapted to be brought into a position under an apertured lock lug 42 secured to the car body 11, and 35 which members 41 and 42 are adapted to receive a seal for securing the operating lever 36 to prevent the door sections from being operated.

40 To press the rear end portions of the door sections toward the car body 11, at the completion of their closing movements, there is pressed from the outer plate 24 of each of said sections a cam 43 arranged to engage the shaft 33, as best shown in Fig. 4. With 45 the cams 43 in engagement with the shaft 33, the door sections are so held that their beads 26 form tight joints between said door sections and the respective door post for the door opening 12.

50 To lock the door sections together when closed, there is mounted on the intermediate section 14 a rotatable disc 44 to which is attached at diametrically opposite points a pair of oppositely extended lock bars 45, the outer ends of which are slidably mounted in keeper brackets 46 on said door section, and adapted to be projected into keeper brackets 47 on the door sections 13 and 15. When 55 the door sections are closed, the upper gear 31 is in mesh with the upper rack, and the

lower and intermediate gears are out of mesh with the respective latch. On the adjacent edges of the door sections are front and rear overlapping lugs or abutments 48.

To open the door sections, the shaft 33 is rotated by the operating lever 36. As the upper toothed wheel 31 is in mesh with the rack on the upper door sections 13, and the intermediate and lower toothed wheels 31 are out of mesh with the respective rack, the 75 door section 13 will be first moved to an open position while the other door section remains closed. Just before the final opening movement of the upper door section 13, its front abutment 48 engages the rear upper abutment 48 on the door sections 14 and imparts the initial opening movement of the door section to bring its rack into mesh with the intermediate toothed wheel 31 before the upper toothed wheel 31 moves out of mesh with the respective rack. A continued movement of the shaft 33 will open the intermediate door section 14 and just before its final opening movement, its front lower abutment 48 will engage the rear abutment on the lower door section 15 and impart the initial 80 opening movement thereto to bring the lower toothed wheel 31 in mesh with the respective rack before the intermediate toothed wheel 31 moves out of mesh with its respective rack. Further continued movement of the shaft 33 will open the door section 15. When the door sections are all open, the upper and intermediate toothed wheels 31 are out of mesh with their racks, and the lower toothed wheel 31 is in mesh with its rack. By reversing the direction of rotation of the shaft 33, the door sections are closed in reverse order from that of their opening 90 movement.

To form grain-tight and weather-proof joints between the door sections, their outer plates 24 are provided at their adjacent edges with overlapping outwardly curved concentric flanges 49, and by reference to Fig. 3 it will be noted that the outer flange 49 is formed with the upper door section so as to form a water-tight joint. These flanges 49 also assist in supporting the intermediate door section and keep the same in its proper relation with the other door sections with freedom for sliding movement in respect thereto.

What I claim is:

1. A car door comprising a flat plate and a concavo-convex plate, the marginal edge portions of which are rigidly secured to the flat plate, and a plurality of horizontally spaced seats formed in the concavo-convex plate to afford a rack for a toothed wheel. 120
 2. A car door comprising a flat plate and a concavo-convex plate, the marginal edge portions of which are rigidly secured to the flat plate, said concavo-convex plate having pressed therefrom a horizontal reinforcing 125
 130

rib having a plurality of horizontally spaced seats affording a rack for a toothed wheel.

3. A car door comprising a flat plate and a concavo-convex plate, the marginal edge portions of which are rigidly secured to the flat plate, said concavo-convex plate having pressed therefrom in the vicinity of its horizontal edges a pair of horizontal reinforcing ribs, one of which has a plurality of 10 horizontally spaced seats affording a rack for a toothed wheel.

4. A car door comprising upper and lower slideable sections having at their adjacent horizontal edges laterally projecting flanges 15 slidably mounted, the one upon the other, and also having at said edges joint and weather strips that having sliding interlocking engagement and hold said sections against vertical separation.

5. A car door comprising upper and lower slideable sections, each of which comprises inner and outer plates, the former of which have at their adjacent horizontal edges sliding engagement the one upon the other and 25 the latter of which have at their adjacent horizontal edges joint and weather strips.

6. A car door comprising upper and lower slideable sections, each of which comprises inner and outer plates, the former of which 30 have laterally projecting flanges slidably mounted, the one upon the other, and the latter of which have at their adjacent horizontal edges joint and weather strips that have sliding interlocking engagement and 35 hold said sections against vertical separation.

7. The combination with a car body having a door opening and top and bottom tracks, of a door for said opening comprising 40 upper, lower and intermediate sections slidably mounted the one upon the other, said lower section being mounted on the bottom track, said upper section being suspended from the top track, and said intermediate section having sliding interlocking engagement with said upper and lower sections, whereby the same is slidably suspended from said upper section and slidably supported on said lower sections.

8. The structure defined in claim 7 in further combination with locking means for securing one of said sections to the car body in a closed position, and a lock for securing 55 all of said sections together when adjusted to form a complete door.

9. The combination with a car body having a door opening, of a door for said opening comprising upper and lower slideable sections, each of said sections having a horizontal rack, an upright shaft outward of 60 said sections and journaled to the car body and having upper and lower toothed wheels meshing with the racks, said racks being arranged so that the upper toothed wheel is 65 in mesh with the respective rack and the

lower toothed wheel is out of mesh with the respective rack when the door sections are closed.

10. The structure defined in claim 9 in which said racks are further arranged so 70 that the upper toothed wheel is out of mesh with the respective rack and the lower toothed wheel is in mesh with the respective rack when the door sections are open.

11. The structure defined in claim 9 in 75 further combination with horizontally spaced abutments on said sections, one of the abutments on said upper section being arranged to engage one of the abutments on said lower section and impart thereto the 80 initial opening movement during its final opening movement to thereby cause the lower toothed wheel to mesh with the respective rack, another abutment on the lower section being arranged to engage another abutment 85 on the upper section and impart thereto the initial closing movement during its final closing movement to thereby cause the upper toothed wheel to mesh with the respective rack.

12. The combination with a car body having a door opening, of a horizontal slideable door for said opening and having a horizontal rack, an upright shaft outward of the door and journaled on said body, and a 95 toothed wheel on the shaft meshing with the rack, said door having a cam arranged to engage said shaft during its final closing movement to press the door against the car body.

13. The structure defined in claim 9 in further combination with a vertical cam flange on the car body with which the front vertical edges of the door sections engage during their final closing movement to press 105 said sections against the car body.

14. The structure defined in claim 9 in further combination with co-operating cam flanges on the car body and door sections for supporting the rear ends of said section 110 when open.

15. The structure defined in claim 9 in further combination with stop members on the car body for limiting the opening movement of the door sections, said sections and stop members having co-operating cam flanges for supporting the rear end of said sections when open, the cam flanges on the stop members being arranged to draw the door sections toward the car body.

16. The structure defined in claim 9 in further combination with an operating lever applied to the shaft, and a pawl and ratchet connection between said shaft and lever, said pawl being reversible to change the 125 direction of rotation of said shaft.

In testimony whereof I affix my signature.

AXEL H. BURKEMAN.
